UNITED STATES PATENT OFFICE

STEPHEN BARACATE, OF TROY, NEW YORK

ELECTRIC ROLL LAUNDRY IRON

Application filed September 18, 1929. Serial No. 393,514.

The object of my invention is to provide a novel electric laundry iron having a plurality of rollers containing the heating elements; to provide a device of this sort which is readily accessible for repairs or replacement of the parts; and to provide a device of this sort in which the rolls are independently separate and interchangeable; and to provide the novel combination and arrangement of parts described and shown.

I attain the objects of my invention by the device illustrated in the accompanying drawings, in which,

Figure 1 is a top plan view of my invention, with a portion of the top plate broken away, and partly in central, horizontal, longitudinal section;

Fig. 2 is a side elevation of my invention, partly in section;

Fig. 3 is an end elevation, partly in section; and

Fig. 4 is a vertical section on line 4—4 of Fig. 2.

Like numerals designate like parts in each of the several views.

Referring to the accompanying drawings, members 1 and 2 are complementary, substantially L-shaped carriage members forming a hollow frame having bearings 5 in which are mounted the hubs or trunnions 4 of the electric heating rolls 3. Members 1 and 2 are suitably fastened together as by screws 17.

The electrically heated ironing rolls 3 are hollow, containing a suitable electric heating or resistance element 9, one terminal 11 being in contact with the contact member 15, while the other terminal 10 is in contact with the contact member 22 which is connected with one strand 14a of the electric cable, while the contact member 15 is electrically connected with the other strand 14b of the electric cable 14.

I provide a suitable bushing 12, insulating the terminal 11 and contact member 15 from the terminal 10 and contact member 22; and I provide another suitable bushing 13, insulating terminal 10 and contact member 22 from the head 6 of the rolls.

I provide suitable screws 8 for fastening

the head 6 to the heating rolls 3. I provide a suitable spring element 16 fastened to the frame and engaging the end of contact member 15 to resiliently retain that element and the elements 22 in contact with the terminal 11 and 10 at all times. I provide a suitable cover plate 18 which is fastened to the frame 1 and 2 by suitable screws 19. I provide a suitable handle 20 to fasten on the cover plate in any suitable manner, as by the screws 21. The element 23 is a conventional socket to receive the plug attached to the electric cable that leads to a floor plug in an electric lighting socket.

In operation, the heated rollers thoroughly iron the clothes and will not pucker or wrinkle damp clothes as a flat faced iron may do. Nor will my iron burn the clothes as readily as would a flat faced iron. Also as the rollers may be readily removed by unscrewing or removing the cover plate 18 and lifting them out, a roller requiring repairs may readily be removed and replaced at will.

What I claim is:

1. In an electric laundry iron, the combination of a hollow frame consisting of a pair of complementary L-shaped members detachably fastened to each other, said members having opposite bearings, ironing rollers having hubs removably mounted in said bearings, electrical resistance elements in the said rollers, terminals for the respective ends of said electrical resistance elements, corresponding insulated contact members in contact with the aforesaid terminals, a wire cable having its strands electrically connected with the respective contact members, means for retaining said contact members in contact with the terminals, and an electric socket mounted on the iron and to which said cable leads.

2. In an electric laundry iron, the combination of a hollow frame consisting of a pair of complementary L-shaped members detachably fastened to each other, said members having opposite bearings, ironing rollers having hubs removably mounted in said bearings, electrical resistance elements in the said rollers, terminals for the respective ends of said electrical resistance elements, corre-

sponding insulated contact members in contact with the aforesaid terminals, a wire cable having its strands electrically connected with the respective contact members,
5 means for retaining said contact members in contact with the terminals, an electric socket mounted on the iron and to which said cable leads, a cover plate carrying a handle, said cover plate being detachably secured to the
10 aforesaid frame members.

3. In an electric laundry iron, the combination of a hollow frame consisting of a pair of complementary L-shaped members detachably fastened to each other, said members having opposite bearings, a plurality of interchangeable ironing rollers having hubs removably mounted in said bearings, electrical resistance elements in the said rollers, terminals for the respective ends of said
20 electrical resistance elements, corresponding insulated contact members in contact with the aforesaid terminals, a wire cable having its strands electrically connected with the respective contact members, means for retaining said contact members in contact with the terminals, and an electric socket mounted on the iron and to which said cable leads.

4. In an electric laundry iron, the combination of a hollow frame having recesses to
30 releasably receive the hubs of rollers, a removable cover on the frame to permit of lifting the rollers from the recesses in the frame, a plurality of electrically heated rollers interchangeably mounted in said frame and without protruding parts, said rollers having free rotary movement, a cable for conducting electric current to said rollers, means for electrically connecting said cable with the electrical resistance elements within
35 the rollers during rotary movement while in use.

5. In an electric laundry iron, the combination of a hollow frame having recesses for releasably seating the hubs of rollers, a cover
45 plate detachably secured to the hollow frame to permit of lifting the rollers from the recesses in the frame, a plurality of electrically heated rollers interchangeably mounted in said frame and without protruding parts,
50 said rollers having free rotary movement, a cable for conducting electric current to said rollers, means for electrically connecting said cable with the electrical resistance elements within the rollers during rotary movement while in use, the rollers having removable heads whereby access may be had to the interior of the rollers for the purpose of repairs or replacement of parts.

STEPHEN BARACATE.
